UNITED STATES PATENT OFFICE

THOMAS DANQUARD, OF NEW YORK, N. Y., ASSIGNOR TO AUTOPIANO COMPANY, OF NEW YORK, N. Y., A CORPORATION OF NEW YORK.

TRACKER-BAR MECHANISM.

No. 902,478.

Specification of Letters Patent.

Patented Oct. 27, 1906.

Application filed July 23, 1906. Serial No. 327,264.

To all whom it may concern:

Be it known that I, THOMAS DANQUARD, a citizen of the United States, residing at New York, in the county of New York and State 5 of New York, have invented a new and useful Tracker-Bar Mechanism, of which the following is a specification.

My invention relates to that type of music playing devices in which means is provided 10 for using music sheets of two different kinds on the same instrument or attachment; that is, music sheets in which the perforations are made on different scales whereby different ranges of operation are provided for.

15 The principal objects of the invention are to provide for accomplishing the desired results by simple means.

Stated broadly, my invention includes the provision of a tracker-bar for one range of 20 notes which is preferably stationary, and a movable tracker-bar for another; the movable tracker-bar lifting the music sheet off of the other bar when it is advanced, and being withdrawn from the music sheet when it is 25 retracted. I also employ means for closing the channels in the tracker-bar which is to be inactive.

Reference is to be had to the accompanying drawings which illustrate two forms in 30 which my invention may be embodied, and in which

Figure 1 is an elevation of a portion of an instrument showing one form. Fig. 2 is a longitudinal sectional view of the same. 35 Fig. 3 is a fragmentary view similar to Fig. 2 showing the parts in a different position. Fig. 4 is an elevation of a portion of an instrument showing another form in which the invention may be embodied, and Fig. 5 is a 40 longitudinal sectional view of the same.

The invention is shown as being provided with the usual music rolls 10 and 11 and between them a tracker-bar 12 which may be of any ordinary construction. This tracker-bar 45 may be provided with the usual number of channels or with any other number, and is preferably stationary.

For the purpose of enabling the instrument to be played with music sheets perforated on a different scale from those which are used with the tracker-bar 12, I have provided another tracker-bar 13 having a different number of channels. This tracker-bar is made movable in guides 14 so that it may be 55 placed in a position forward of the tracker

bar 12 or behind it. When placed forward, it is intended to lift the music sheet passing from one roll to the other to such a degree that the sheet will not engage the bar 12. When it is moved behind it, it is intended to 60 be moved sufficiently to be out of engagement with the music sheet as it passes naturally over the bar 12. This is preferably accomplished by moving the bar 13 along a line parallel with the bar 12 or in other words, 65 perpendicular to its front face. This explains the general nature of the invention and the operation thereof.

For the purpose of permitting the two tracker-bars to be used in a convenient manner, the channels of the bar 12 are connected by stationary rigid tubes 15 with channels 16. The channels of the movable bar are rigidly connected with the same set of channels 16 by means of flexible tubes 17. 70

The parts so far described are common to the two forms of the invention illustrated in the drawings.

I have also provided for covering the channels of the inactive bar so as to prevent the 80 passage of air therethrough. This means is shown in different forms in the two sets of figures. In Figs. 1, 2 and 3 it comprises a movable cap-plate 18, in this instance shown as pivotally mounted upon a sliding strip 19 85 located between the tracker-bars and reciprocable their full width. At the ends of the tracker-bars stationary blocks 20 are mounted, and a pair of springs 21 are provided, connected with the strip 19 for forcing the 90 latter onto the blocks 20, these springs being capable of yielding to permit the strip to advance.

The tracker-bar 13 is provided with a hook 22 which is adapted to engage the strip 19 95 when the tracker-bar is advanced, and to move the strip with it during the rest of the stroke of the tracker-bar. A spring 23 is connected with the cap-plate 18 at a point beyond that at which it is pivoted to the 100 strip 19, and at the right thereof; that is, when the cap-plate is in a position parallel with the strip 19 between the two tracker-bars during the travel of the tracker-bar 13, the spring tends to move the cap-plate over 105 the tracker-bar 13, and when the latter is retracted far enough to permit this operation it will be performed automatically by the spring.

The movement of the tracker-bar 13 in an 110

outward direction first results in swinging the cap-plate away from the channels in the tracker-bar and later gives motion to the strip 19 and cap-plate with the tracker-bar, 5 caused by the hooks 22.

When the cap-plate reaches a position in which it can over-lap the stationary tracker-bar 12, the force of the spring 23 normally prevents it from assuming this position, and, 10 therefore, I have shown a pair of deflecting plates 24 against which the cap-plate engages to cause it to be swung over toward the tracker-bar 12. After it has been swung past the center, the spring 23 will act in the 15 other direction to force the cap-plate onto the bar and hold it there under some tension.

It is to be noted that the cap-plate is provided with concaved surfaces 25 on both sides, or fitting the convex surface of the 20 tracker-bars, when tracker-bars of that shape are employed. Furthermore, the motion of the tracker bar 13 is preferably sufficient in extent in both directions to prevent the music sheet engaging the cap-plate which is 25 in position over the channels of the tracker-bar which is inactive.

A handle 26 is shown for manipulating the tracker-bar 13, and it will be observed that all the motions of the tracker-bar, cap-plate 30 and music sheet are performed by the simple manipulation of this handle.

In the form shown in Figs. 4 and 5 a somewhat simpler arrangement of cap-plate is shown, but one which operates automatically only in part. In this form a pair of cap- 35 plates 18' and 19' are employed.

The cap plate 18' is mounted on a slide 20' which has a spring 21' engaging a projection 22' from the cap plate to force it over the 40 face of the tracker-bar when the slide is advanced. A lever 23' is provided for manipulating the slide. The cap-plate 19' is mounted on a lever 24', and a spring 25' is employed for automatically forcing it over 45 the tops of the channels in the bar 13 when the latter is retracted for shutting them off.

While I have illustrated and described two particular forms in which my invention may be embodied, I am aware that many modifications may be made therein by any person skilled in the art without departing from the 50 scope of the invention as expressed in the claims.

Having thus fully described my invention, 55 what I claim and desire to secure by Letters Patent is:—

1. In a music playing device, the combination of a stationary tracker-bar, a movable tracker-bar, and a guide for the movable 60 tracker-bar parallel therewith and extending both in front of and behind the front face of the stationary bar, whereby the movable bar may be advanced in front of or retracted behind the stationary bar.

65 2. In a music playing device, the combina-

tion of a stationary tracker-bar with a movable tracker-bar reciprocable parallel with and both in front of and behind the stationary tracker-bar:

3. In a music playing device, the combination of a stationary tracker-bar, a tracker-bar movable to position in front of and behind the first bar, and means for automatically closing the channels in each tracker-bar when the other is beyond it. 70

4. In a music playing device, the combination of a set of primary pneumatics a stationary tracker-bar, and a movable independent tracker-bar, the channels of the two tracker-bars being connected with the set of 80 primary pneumatics.

5. In a music playing device, the combination of a stationary tracker-bar with a movable tracker-bar reciprocable to a position in front of and behind the first named bar, and 85 means for automatically closing the channels of the first bar when the movable bar is moved beyond it, and of the movable bar when it is retracted behind the first bar.

6. In a music playing device, the combination of a stationary tracker-bar, a movable tracker-bar, a cap-plate, and means for automatically moving the cap plate over the channels in each of the bars when it is in a position beyond the other. 90

7. In a music playing device, the combination of a pair of tracker-bars one of which is movable, a cap-plate therefor, and means operable by the movement of one bar for removing the cap-plate alternately from each 100 bar when in advance of the other and applying it to the other bar.

8. In a music playing device, the combination of a tracker-bar, a sliding strip, a cap-plate pivotally connected with the sliding strip, and means for swinging the cap-plate 105 over the tracker-bar.

9. In a music playing device, the combination of a movable tracker-bar, a sliding strip, resilient means for normally forcing the strip to the rear of said bar, means on the bar for moving the strip forward with it, a cap-plate on the strip, and a spring adapted to force the cap-plate over the bar. 110

10. In a music playing device, the combination of a pair of tracker-bars one of which is movable, a sliding strip, a cap-plate pivotally connected with the sliding strip, and means for swinging the cap-plate over one of the bars when it is behind the other. 115

11. In a music playing device, the combination of a pair of tracker-bars one of which is movable, a sliding strip between the bars, yielding means for normally forcing said strip towards the rear of the bars, means on one 125 of the bars for moving the strip therewith, and a cap-plate on the strip for covering the channels of the bars.

12. In a music playing device, the combination of a pair of tracker-bars one of which 130

is movable, a sliding strip located between them, resilient means for normally forcing the strip to the rear of said bars, means on one of the bars for moving the strip forward 5 with it, a cap-plate on the strip, and a spring adapted to force the cap-plate on either bar.

13. In a music playing device, the combination of a pair of tracker-bars one of which is movable, a sliding strip mounted between them, a cap-plate pivotally connected with 10 said strip, resilient means for normally forcing the strip against the surface of one of said bars, a deflector for swinging the strip in the opposite direction when the last named bar 15 is moved into an advanced position, said resilient means being adapted to force the cap-plate onto the other bar after it is deflected by said plate.

14. In a music playing device, the combination of a movable tracker-bar, a cap-plate therefor, resilient means tending to force the cap-plate over the movable bar when the latter is retracted into inactive position, and means for moving the bar forward, the movement of the bar forcing the cap-plate away 25 from the channels thereof.

15. In a music playing device, the combination of a tracker-bar, a cap-plate for the

conduits of the tracker-bar, a slide on which the cap-plate is pivotally mounted, and a 30 spring on said slide for swinging the cap-plate over the conduits.

16. In an automatic musical instrument or player in combination with a traveling controller sheet, a duplex tracker device comprising two elements having duct mouths spaced according to different scales, said elements being mounted one behind the other along the path of travel of the controller; means for moving said elements relatively to 40 each other to protrude either at will beyond the other toward the controller; a single set of tubes and means by which they communicate with the ducts of both elements; a valve bar for closing the duct-mouths of one of said 45 elements hinged and operated by the relative movement of said elements for swinging to and from such duct-closing position.

In testimony whereof I have hereunto set my hand, in the presence of two subscribing 50 witnesses.
